Primary Examiner — Lauren D McVey(74) *Attorney, Agent, or Firm* — Knobbe Martens Olson & Bear LLP(57) **CLAIM**

The ornamental design for a monitor arm, as shown and described.

DESCRIPTION

FIG. 1 is a first perspective view of a monitor arm showing the new design;

FIG. 2 is a second perspective view thereof;

FIG. 3 is a left side view thereof;

FIG. 4 is a right side view thereof;

FIG. 5 is a rear elevation view thereof;

FIG. 6 is a front elevation view thereof;

FIG. 7 is a top plan view thereof;

FIG. 8 is a bottom plan view thereof;

FIG. 9 is a perspective view of the monitor arm, in an example environment;

FIG. 10 is another perspective view of the monitor arm, in an example environment; and,

FIG. 11 is another perspective view of the monitor arm, in an example environment.

Broken lines are used to illustrate features of the monitor arm that form no part of the claimed design.

1 Claim, 11 Drawing Sheets(56)
